PHONOGRAPHIC SYSTEM

Charles T. Jacobs, New Providence, N. J., assignor
to Thomas A. Edison, Incorporated, West Orange, N. J., a corporation of New Jersey

Application April 15, 1936, Serial No. 74,449

20 Claims. (Cl. 274—18)

This invention relates to phonographic systems, and more particularly to means and methods for controlling and indicating the operation thereof.

While not in all aspects limited thereto, the invention has especial reference to systems comprising a plurality of phonographs adapted for alternate, or sequential, operation to provide uninterrupted recordation of continuing matter. The control means most particularly contemplated by the instant invention are such as may be manipulated, for example, by a dictator, at a point remote from the phonographs proper, an attendant then for example successively supplying the phonographs with fresh records and restoring them to recordation initiation conditions, as required.

A system according to the invention desirably, though not indispensably, may involve the use for each phonograph of starting and stopping means of the type responsive to momentary actuation—such for example as shown and described in connection with such systems in the co-pending application of Charles Heunlich, Serial No. 581,870, filed December 18, 1931, on which Patent No. 2,042,228 has since been issued. As is known, having been therein shown, the employment of such means in a system of sequentially operating phonographs is attended with the danger, if uncounteracted, of a start-stop oscillation under certain conditions of portions of the system. An object of the instant invention is the prevention, in novel and improved manner, of such oscillation.

Another object is the provision of improved and reliable protective means for a system of the class described.

Another object of the invention is the arrangement of appropriate control system elements for plural phonographs in a novel and simple manner.

Another object is the arrangement of such elements in manner facilitating the association therewith of appropriate indicating means for both dictator and attendant.

Another object is the provision of a simplified such control system.

Another object is the provision of a control system involving a particularly small number of conductors joining the dictator's control station with the phonographs proper.

Another object is the provision of a generally improved plural phonograph system, particularly for sequential phonograph operation.

Still another object is the provision of more extensive indications to the attendant of the condition of the system, and of improved means for providing indications for the attendant.

Still another object is the simplification of the indicating means for the dictator.

Still another object is the provision of generally improved and simplified indicating means in a system of the class described.

Other and allied objects will more fully appear from the following description and the appended claims.

In the description reference is had to the accompanying drawings, of which:

Figure 1 is a schematic diagram of an embodiment of my invention in a system of two phonographs and control station therefor;

Figure 2 is a like diagram of an alternative embodiment of my invention, some of the components of the control station appearing in cross-section; and

Figure 2a is a fractional control station view intended for optional substitution for the corresponding portion of Figure 2, illustrating a modification thereof.

Reference is first invited to Figure 1, wherein have been illustrated the plurality of phonographs comprising phonographs A and B, the control station C, and the phonograph coupling unit D. The phonographs proper may first be described, with particular reference to phonograph A; it will be understood that phonograph B is mechanically similar, its illustrated components having been designated with numbers similar to those for the corresponding components of phonograph A, excepting that they have been furnished with prime marks. Each phonograph may comprise for example a mandrel 10 adapted to carry a cylindrical record; a sound box 7 adapted to record on and/or reproduce from such a record and adapted to be driven longitudinally thereof as along a guide 8 by means of feed screw 8a; and a motor M suitably arranged to produce rotational movement of the mandrel and longitudinal movement (in a right-hand direction as illustrated) of the sound box. The sound boxes may be of any known variety, as may also the means for energizing the same—not shown herein because forming no part of the instant invention.

Optionally there may also be included in each phonograph a clutch L interposed between the motor and the parts thereby moved; it is to be understood, however, that the illustrated inclusion of these clutches has not rendered the system as shown a completely clutch-controlled one.

In respect of general elements and their coordination, the control arrangements illustrated for the system may be described as comprising separate operation control members for the sev-

- 5 general phonographs, and a common operation control member for all the phonographs, these being so arranged that each phonograph will operate only when both the respective individual member and the common member occupy their "run" positions, and will be stopped when either the respective individual member and/or the common member occupies its "stop" position; an automatic system, including starting and stopping circuits, energizable to position the individual control members in accordance with sound box positions in the several phonographs, typically to provide sequential operation of the phonographs; an arrangement of the common control member to be responsive to simple manipulations by the dictator for placing the system in and out of operation, without auxiliary manipulations or manipulations selective as to the several phonographs or manipulations variant according to preceding performance of the system, and with assurance of maintenance of proper phonograph operational sequence; and protective means for preventing objectionable effects otherwise tending to occur when the system becomes temporarily incapable of further recordation, as by virtue of all sound boxes being at or adjacent their terminal travel limits.
- 10 The supply of current for the entire system may be derived from any suitable supply line as through the plug 13, rendering at respectively opposite line potentials the conductors 11 and 12. The conductor 12 has been shown leading only to the pole 14b of the main line switch 14 in the control station C, to the co-operating contact spring 14a of which is connected the conductor 12a leading from the control station into the coupling unit and thence into each phonograph; the conductor 12a is of course invested with the potential of conductor 12 when the switch 14 is closed (e. g., pole 14b touching contact spring 14a), which will be assumed throughout the balance of the description. It is also convenient in the balance of the description as to Figure 1 to assume operation of the system on direct current, so that typical simultaneous polarities of several 15 of the conductors may be noted in the figure and referred to; it will be understood, however, that this procedure is purely to facilitate the exposition of the circuit functions, and is in utterly no sense limitative to the indicated polarities or to direct current operation. In accordance with this procedure, conductor 11 may be considered the negative line conductor, and conductor 12 (together with 12a when switch 14 is closed) the positive one.
- 20 55 The individual control member for each phonograph may be an arm 27 therein, immediately responsive to a magnet assembly 100 and there-through to the automatic system of starting and stopping circuits hereinafter described. Each magnet assembly may comprise a pair of stop and start electromagnets (20 and 21, respectively), the control arm being responsive in its position to the last actuated of the two magnets; preferably the magnet assembly has associated therewith a switch arranged upon each control arm response to open-circuit the magnet to which the response has occurred. A variety of systems are obviously available for the control arm, magnet assembly and switch; but I have preferred to employ for this purpose, and have schematically illustrated, a system which is in accordance with the teachings of U. S. Letters Patent to Langley, No. 1,380,486, issued June 7, 1921.
- 25 70 75 Herein the control arm 27 comprises an ar-

ture portion 28 arranged for alternate attraction by the magnets; and the switch conveniently includes the control arm itself as a pole, connected for example to the positive conductor 12a, and a pair of contacts 22 and 23 respectively in series with the stop and start magnets 20 and 21, the control arm having two possible positions only—i. e., touching one or the other of the contacts. The actuation of each magnet is effected through the switch; and it will be seen that the contacts are so arranged that the control arm comes to a position touching one (e. g., in phonograph A, touching contact 22, in series with stop magnet 20) in response to actuation of the respectively opposite magnet (e. g., start magnet 21), the latter magnet being thereby open-circuited at its series contact (e. g., 23). This arrangement, wherein each magnet upon actuation both throws the control arm and open-circuits itself, has among its distinct advantages those of obviating wasteful and excessively heating continuations of current flow through the magnet, and of enforcing a strictly alternate actuation of the two magnets.

The run position of the control arm is that which has been illustrated in phonograph A; in that phonograph the start magnet 21 has last been actuated to attract the arm, and the stop magnet series contact 22 is being touched by the arm (the respectively opposite arm position and conditions having been shown as obtaining in phonograph B). Therefore to render each control arm effective to permit operation of the respective phonograph only when it is in the run position, the power supply to one side of the respective motor may be taken from the positive conductor 12a to that motor side through the control arm (e. g., 27) and the stop magnet series contact (e. g., 22); each motor is thus deprived of power when the respective control arm is in its stop position, touching contact 23, and the respective phonograph is accordingly then out of operation—i. e., its mandrel is stationary. It is permissible, however, to make the electrical connection of the mentioned side of each motor to the conductor 12a directly, and to rely for the function of the respective control arm on a mechanical connection thereof to the respective one of the optionally included clutches. This connection has been schematically illustrated in each phonograph as a lever 26 or 26'; when the control arm and hence the lever are to the left (as shown in phonograph B) the clutch will be understood to be disengaged, and when to the right (as in phonograph A) the clutch will be understood to be engaged.

The other side of each of the motors may be connected to a common conductor 11b (shown in Figure 1 as a heavy line); and it may be the function of the common control member above mentioned to connect and disconnect this conductor to and from the negative line conductor 11. The common control member in Figure 1 has been shown as the arm 327 (connected to negative conductor 11) of a magnet assembly or relay 400 contained in the coupling unit D; this magnet assembly 400 may include components respectively similar to all those of the magnet assembly 100 above described, these having been designated with numerals higher in each instance by 300 than those of that assembly. An appropriate contact co-operating with the arm 327 is to be connected to the conductor 11b so that following actuation of the start and stop magnets 321 and 320, respectively, the conductor 11b will be con-

nected to and disconnected from the conductor 11. While the stop magnet series contact 322 may be employed for this function, I prefer to employ a separate contact 322b insulated therefrom—but in such alignment therewith that when arm 327 (which may be appropriately lengthened, for example) is in its run position touching contact 322 it is also touching contact 322b.

The magnet assembly 400 may be controlled by a pair of openly biased switches in the control station, each having one terminal connected to the positive conductor 12a—a stopping switch 380 having its second terminal connected to the non-contact extremity of stop magnet 320 through conductor 380a, and a starting switch 381 having its second terminal connected to the non-contact extremity of start magnet 321 through conductor 381a. It being borne in mind that the internal functioning of the magnet assembly 400 is quite like that set forth for the magnet assembly 100, it will be seen that so long as common control arm 327 is in run position (preparing the stop magnet for actuation) momentary closure of stopping switch 380 will throw it to stop position, breaking the supply of power to the motors; while so long as common control arm 327 is in stop position (preparing the start magnet for energization) momentary closure of starting switch 381 will throw it to run position, re-connecting conductor 11b with conductor 11. The stopping and starting switches 380 and 381, respectively having for example the manipulating buttons 380b and 381b, carried by the respective pivoted poles 380c and 381c, may obviously be arranged if desired with these poles in rigid mutual alignment about a single pivot, or otherwise to form an intermediately biased single pole, double-throw switch.

It may here be noted that while the dictator will usually stop operation of the system by momentarily pressing the stop switch button 380a, throwing the common control arm 327 to stop position, he may at times simply open the main line switch 14, leaving control arm 327 in run position. In the latter case only, simple re-closing of the switch 14 would cause an immediate and probably premature operation of the system. In order to insure the assumption by control arm 327 of stop position upon stopping of the system, however effected, a spring contact 14c may be associated therewith, untouched by pole 14b when switch 14 is closed but, in the process of opening of switch 14, touched by the pole 14b before the latter leaves contact with spring 14a. This extra spring contact 14c is connected to the conductor 380a, so that the connection of this conductor to 12a before opening of switch 14 is insured; this is obviously equivalent to the momentary closing of switch 380, and thus throwing of the control arm 327 upon any stopping of the system is insured.

Attention may now be directed to the automatic system of stopping and starting circuits. The stopping circuit for each phonograph is a local circuit therein, including the respective stop magnet (20 or 20') and switch means arranged to be closed (and thus to actuate the stop magnet) as the sound box reaches its terminal travel limit; while the starting circuits extend between the several phonographs, this circuit for each phonograph including the respective start magnet (21 or 21') and switch means associated with another of the phonographs and arranged to be closed when the sound box in such other phonograph approaches its terminal travel limit—this closing of the circuit actuating the start magnet included

in the circuit. Such automatic system of starting and stopping circuits is in itself well known; but I associate therewith a novel protective circuit, having switch means in each phonograph associated with the automatic system switch means therein, the protective circuit co-operating with the starting and stopping circuits to prevent certain misfunctions of those circuits as will hereinafter be apparent.

The switch means in each phonograph for stopping, starting and protective circuits may comprise a group of three normally open switches adapted to be progressively closed as the sound box in that phonograph approaches its terminal travel limit; these switches, in the order of their closings, may be termed the "protective" switch, the "successive starting" switch, and the "self-stopping" switch. They have been illustrated in each phonograph as formed by five contact springs (e. g., 6, 5, 3, 2, 1 in phonograph A); spring 6 being adapted upon rightward movement to be closed against spring 5, spring 5 being connected with spring 3 by an insulating tie-rod or -block b, and spring 3 being adapted (by continued rightward movement of spring 6) to be closed against spring 2 and finally (through spring 2) against spring 1. Springs 6 and 5 together form the protective switch 56, and springs 3 and 1 (mutually closeable through spring 2) form the self-stopping switch 31, for the phonograph with which they are associated; while springs 3 and 2 together form the successive-starting switch 32 for another phonograph. The spring 6 is adapted for rightward movement (to close successively the several switches) as the sound box approaches its terminal travel limit, as by a projection 9 therefor provided on the sound box and adapted to impinge against spring 6. The description of the switch means has been given specifically with reference to phonograph A; but it will of course be understood that corresponding switch means, sound box projection, etc., are provided in phonograph B, their designating numerals being provided with prime marks.

To energize the automatic system contact springs 3 and 3' are connected to the negative conductor 11. (For reasons hereinafter apparent this connection is desirably made through the switch formed by contact 322b and common control member 327—i. e., through conductors 11c and 11c' to conductor 11b—so that it will be effective and the automatic system energized only when control member 327 occupies its run position.) The contact springs 1 and 1' are respectively connected to the non-contact extremities of the stop magnets 20 and 20' through the respective conductors 54 and 54'. The stopping circuit for phonograph A may be traced from spring 3 to the positive conductor 12a through the self-stopping switch 31, conductor 54, stop magnet 20, contact 22, and control arm 27. Analogously the stopping circuit for phonograph B may be traced from spring 3' to the positive conductor 12a through the self-stopping switch 31', conductor 54', stop magnet 20', contact 22', and control arm 27'.

Contact spring 2' (in phonograph B) is connected to the non-contact extremity of start magnet 21 (in phonograph A) through the conductor 40, and analogously contact spring 2 (in phonograph A) is connected to the non-contact extremity of start magnet 21' (in phonograph B) through the conductor 40'; both these conductors 40 and 40' may conveniently pass through the coupling 76

unit D. The starting circuit for phonograph A may be traced from spring 3' (in phonograph B) to the positive conductor 12a through the successive starting switch 32', conductor 40, start magnet 21, contact 23, and control arm 27. Analogously the starting circuit for phonograph B may be traced from spring 3 (in phonograph A) to the positive conductor 12a through the successive starting switch 32, conductor 40', start magnet 21', contact 23', and control arm 27'.

The operation of the automatic system may be described on the initial assumption that the common control member 327 is in run position; that one of the phonographs (e.g., A) is in operation, with its sound box at some intermediate point in its rightward travel; and that the phonograph B is out of, but in readiness for, operation—i. e., has its sound box at its initial or leftward travel limit and has a fresh record inserted upon its mandrel. Since the phonograph A is in operation, its control arm 27 is of course in its run position, completing its motor circuit and placing the stop magnet 20 in condition for next actuation. In phonograph B, out of operation, the arm 27' has last been attracted by the stop magnet 20' to occupy its stop position, placing the start magnet 21' in condition for next actuation. These conditions are those illustrated in Figure 1.

When the sound box projection of the now operating phonograph A impinges against the spring contact 6 there is first closed the switch 56, of which the function is hereinafter described. Upon negligible further travel of the sound box 7 the spring contact 6 will have been sufficiently further moved to close the successive starting switch 32; this closes the phonograph B starting circuit, actuating the phonograph B start magnet 21' and moving the control arm 27' to its run position touching contact 2'; this places the phonograph B in operation. For a brief interval at this juncture both phonographs will be operating, so that a slight overlap of the recordations by the two phonographs will be effected. Still further slight travel of the phonograph A sound box 7 closes the self-stopping switch 31, closing the phonograph A stopping circuit, actuating the stop magnet 20, and moving the control arm 27 to its stop position touching contact 23; this places the phonograph A out of operation. Before the phonograph B sound box 7' approaches the spring contact 6' the phonograph A sound box 7 may be manually moved leftwardly to the beginning of its path of travel, and a fresh record inserted upon mandrel 10.

The conditions of the two phonographs as to operation and component positions will now be seen to be quite reversed from those assumed at the beginning of the preceding paragraph; and the operations of that paragraph are accordingly repeated, but in each case as to the respectively opposite phonograph and components. And upon completion of those operations as to that phonograph and components, the operations precisely as described in the preceding paragraph are repeated; and so on in an automatic progression which so long as common control member 327 remains in run position will be unbroken—except by the failure to restore one of the sound boxes leftwardly to the beginning of its travel path during the travel of the other sound box.

If this failure occurs the system will, in the absence of an appropriate preventive, go into an oscillatory condition. This is readily understood by first supposing the sound box of phonograph

B, for example, to have reached its terminal travel limit, to have closed the switches 56' and 32', starting phonograph A, and finally to have closed switch 31', thus having caused control arm 27' to throw to its stop position, stopping phonograph B and preparing the start magnet 21' thereof for actuation; these conditions are those illustrated in Figure 1 excepting that they involve a rightward sound box position and closed switch 56—32—31' condition in phonograph B. Now when the sound box in phonograph A has progressed to a near-limiting position it will close successive starting switch 32 and thus the phonograph B starting circuit; and so there will be actuated the phonograph B start magnet 21', throwing the B control arm 27' to run position and preparing its stop magnet 20' for actuation. Since self-stopping switch 31' in phonograph B is closed, this stop magnet actuation will immediately occur, throwing the control arm 27' back to stop position. But because successive starting switch 32 is still closed, a re-throwing of arm 27' to run position will immediately occur—and so the arm throwing continues in a sustained oscillation. And almost immediately after closing successive starting switch 32, the continued phonograph A sound box movement will close the A self-stopping switch 31, whereupon it will readily be seen that there will be set up a similar start-stop oscillation of the phonograph A control arm 27. This oscillation will not only comprise an oscillation of each of the control arms 27 and 27' (and clutches if employed), but also with the circuit as shown, if conductor 11b remains meanwhile connected to the supply line, will comprise a start-stop oscillation of each of the two motors.

It is known to obviate this oscillation by automatically opening the starting circuit of each phonograph before the stopping circuit thereof is closed. This is an effective procedure; but it results, at the times when start-stop oscillation would otherwise occur, in occupation by all the control arms (27, 27') of their stop positions. This fact very materially affects the necessary arrangements for the placement of the system in further operation after sound box restoration—an action which should of course occur not merely upon restoration of the sound boxes to their initial travel limits, but rather thereafter in response to a deliberate manipulation by the dictator at the control station—and renders unusable the extremely simple such arrangements which I have shown.

The protective circuit which I incorporate in the system of phonographs prevents this start-stop oscillation in a different manner: it stops the entire system when there is reached a condition of adjacency of both sound boxes to their terminal travel limit, acting just before the latter of the sound boxes to reach such position closes the successive starting switch responsive thereto. It may consist of a circuit—connected from conductor 12a in such manner to conductor 11 that it is capable of functioning at all times when line switch 14 is closed—serially including the protective switches (56, 56') of the several phonographs and a device, responsive to closing of the circuit, for stopping such phonograph as is then in operation. For conservation of components and, more importantly, for rendering entirely similar the subsequent starting manipulation required of the dictator whether the system was stopped by his deliberate closing of switch 380 or by the action of the protective circuit, this device may be the common control

arm 327. For further conservation of components the means for throwing this arm to stop position in response to closing of the protective circuit may be the stop magnet 320. Accordingly 5 the protective circuit—which may begin at the point P (on conductor 12a) in phonograph B and may be traced serially through conductor 57, protective switch 56', conductor 57a, protective switch 56, and conductor 57b—may from the 10 conductor 57b be connected (as at the point Q) to the non-contact extremity of the stop magnet 320.

Because of its functioning in the protective circuit the magnet 320 will preferably after actuation remain energized (as long as the protective circuit is closed) to insure the maintenance by the arm 327 of its stop position; this is preferred in order to obviate the re-throwing of the arm to run position by closure of the dictator's starting switch 381 before sound box restoration (and to obviate the production of start-stop oscillation of the magnet assembly 400 by any prolonged closure of the switch 381). It is not, however, necessary that this continued 25 energization be of the full strength of the initial actuation of this magnet; by its initial actuation and the throwing of arm 327, the armature 328 has been brought near this magnet, and a relatively weak continued energization will be 30 sufficient to obviate re-throwing of the arm 327 in response to any actuation of start magnet 321. Accordingly a resistance 395 may be shunted from arm 327 to contact 322, so that it is shorted when arm 327 is in run position but is 35 rendered effective to cut down the current through the stop magnet 320 and the protective circuit when arm 327 is in stop position. It will of course be obvious that this will result in continued reduced-strength energization of the stop magnet 320 after any actuation thereof by closing of the dictator's stopping switch 380, so long as that switch is held closed; but this is quite permissible in view of the reduced strength of the energization (as well as of the short periods for which this openly biased switch would be 40 so held).

For reasons having to do with the indicating system hereinafter described, it is desirable that some of the resistance which functions to cut down the continued current flow in the protective 50 circuit be inserted in that circuit proper—for example in the conductor 57b. Accordingly it is preferred that not all the permissible resistance be comprised in 395, but that a portion thereof be inserted, as 396, in the mentioned 55 conductor. (Typically the values of 395 and 396 are so apportioned that the total impedance of 395 and that of the stop magnet 320 will approximate that of the resistance 396.) The resistance 60 396, when employed, is of course to be shorted out when the control arm 327 is in run position; accordingly there may be shunted about resistance 396 a switch formed by an arm 397 mechanically linked to that control arm for movement therewith, and a contact 398 against which the arm 65 397 closes when control arm 327 is in run position.

It will now be seen that the protective circuit stops the operation of the motors, by throwing 70 the common control arm 327 to stop position, before the automatic system abortively tries to start the operation of an unstartable phonograph. Thus start-stop oscillation of the motors is effectively prevented and, even though the automatic 75 system were maintained continuously energized,

start-stop oscillation of the magnet assemblies would in the normal course be prevented in view of the complete cessation of sound box travel. But the sound box of the last-operating phonograph might be inadvertently moved, for example 5 manually by the attendant, sufficiently further rightwardly to close the associated successive starting switch, precipitating start-stop magnet assembly oscillation; it is for this and other precautionary reasons that the contact springs 3 10 and 3' are connected to conductor 11 through contact 322b and common control arm 327—the protective circuit upon closing thus functioning to de-energize the automatic system as well as to preclude operation of any phonograph. 15

It is to be noted that the system invariably stops—upon throwing of common control arm 327 to stop position, whether effected by the dictator's stopping switch 380 or by the protective circuit—with the individual control arm of the 20 last-operating phonograph in run position (or, in the more exceptional case of arm 327 having been thrown during a period of overlap, with the control arms of the two phonographs both in run position). It is this which limits the operation 25 required for re-starting to re-throwing of common control arm 327 only (i. e., by momentary closure of dictator's starting switch 381); operation will thereupon be automatically resumed of that phonograph (or phonographs) which were 30 operating at the moment of prior system stopping. It is convenient to bear in mind that whenever 35 the arm 327 is in run position there is in operation one (or during overlaps, two) of the phonographs, as well as the fact that there always remains in run position at least one of the individual control arms (27, 27').

It has been seen that a continued closure of the protective circuit renders the closing of dictator's starting switch 380 ineffective to re-throw common control arm 327 to run position until the closure is broken by the restoration of at least one sound box; thus a non-operation of the system is enforced during that circuit closure. In order that the dictator be apprized (preferably 45 in advance) of such non-operation for this or other causes, and generally to facilitate his intelligent control of the system, it is desirable to provide appropriate indicating means in the control station; at the same time it is desirable that 50 this be done with a minimum of complication of the system and without extra conductors to the control station, and generally in a manner resulting in indications of a high degree of positiveness. Such indicating means, appropriate to the system 55 disclosed, are shown in Figure 1. These means may comprise two pilot lamps 260 and 290, which may respectively be termed "stand-by" and "phonograph" pilots; the stand-by pilot desirably is lit whenever the main line switch 14 is closed 60 and the system is either in operation, or out of but in readiness for operation, while the phonograph pilot is desirably lit whenever either of the phonographs is operating. These lamps are preferably of the neon type, designed for operation 65 with very minute current, and (at least in the case of the stand-by pilot 260) preferably have a minimum igniting voltage materially in excess of half the supply line voltage.

The stand-by pilot 260, in series with a high 70 current-limiting resistance 261, is simply shunted in the control station from the conductor 12a to the stopping switch conductor 380a. Observing the exemplary polarities abovementioned, it is seen that conductor 12a is always positive (of 75

course assuming line switch 14 closed); the potential of conductor 380a, however, varies in accordance with the condition of the system. If the control arm 327 is in run position and the system thus in operation, it is obvious that the conductor 380a is established through stop magnet 320 at negative line potential; accordingly (in view of the very high resistance of 261) substantially full line voltage appears between the conductors 12a and 380a, and pilot 260 will be lit. Again, if the control arm 327 is in stop position without the protective circuit being closed—i. e., in response to the dictator's closing of switch 380, the system being accordingly out of but in readiness for operation—the conductor 380a is again established, this time through both resistance 395 and the stop magnet 320, at negative line potential, and again the pilot 260 will be lit. On the other hand, if the control arm 327 has come into stop position in response to a protective circuit closing which persists—the system thus not being in readiness for further operation—the conductor 380a is established at approximately mid line potential, in view of the division of line voltage between resistance 396 on the one hand and the resistance 395 and stop magnet 320 on the other hand; accordingly only approximately half line potential appears between conductors 12a and 380a, and the pilot 260 will be extinguished. And if the line switch 14 be opened, the pilot 260 will obviously be extinguished. So the times of lighting and extinction of the pilot 260 meet the requirements—the sole exception being the unimportant one that the pilot will be temporarily extinguished during the momentary closings of stopping switch 380 by the dictator.

While it is not in general necessary in a system of this character that the dictator be apprized of the specific machine which is operating, it is desirable that he be apprized of the fact that some one of the phonographs is operating when that is the case, and of the times of shift from operation of one to operation of another of the phonographs—i. e., of the periods of overlap, or joint operation of the two phonographs. To achieve this result certain known systems have employed in their control stations a plurality of phonograph pilots respectively corresponding to the several phonographs. According to my invention, however, this result is achieved by the single phonograph pilot 290; this is done by causing the pilot to light at one degree of brilliance during operation of a single phonograph, and at another degree of brilliance during operation of two. As in the case of the stand-by pilot the phonograph pilot may be shunted between two conductors already necessary in the control station for control purposes, this simple connection being caused to effect the desired results by virtue of appropriate, but also simple, connections in the phonographs and coupling unit.

Thus the phonograph pilot 290, in series with a high current-limiting resistance 291, is shunted in the control station from the starting switch conductor 381a to the stopping switch conductor 380a. An extra contact 22a in phonograph A and an extra contact 22a' in phonograph B are provided in alignment respectively with contacts 22 and 22' therein and adapted to be touched by the respective arms 27 and 27' (thereto appropriately lengthened) at the same times as those contacts (i. e., when the respective arm is in run position); and the contacts 22a and 22a' are connected through respective conductors 292 and 292' and respective high resistances 293 and

293' to the starting switch conductor 381a. If the control arm 327 is in stop position, the conductor 381a is established through start magnet 321 at negative line potential; it was seen above that conductor 380a is then either at mid or negative line potential (depending on the condition of the protective circuit), and accordingly the phonograph pilot 290 will receive not more than approximately half line voltage and will therefore be extinguished. If the control arm 327 is in run position, the conductor 381a receives no potential through the start magnet 321; if now one phonograph is operating (the associated arm 27 or 27' being in its run position) the conductor 381a is connected to the positive conductor 12a through one of the resistances 293 and 293' (and one conductor 292 or 292', one contact 22a or 22a', and one arm 27 or 27'); but if both phonographs are operating (both of the arms 27 and 27' being in their run positions) the conductor 381a is similarly connected but through both the resistances 293 and 293' in parallel, causing an increase of the current through the pilot 290. Accordingly in the three respective cases of neither, one and both phonographs operating the phonograph pilot 290 will be extinguished, lit at moderate brilliance, and lit at high brilliance—the exception being the unimportant one that these indications may be temporarily upset during the momentary operations of the starting and stopping switches 381 and 380 by the dictator.

The pilots thus described are provided for the benefit of the dictator. It is, however, advantageous to have another set of indicating means for the benefit of the attendant; these means desirably comprise an individual "attendant's" pilot lamp for each of the several phonographs, arranged so that each is lit whenever the respective phonograph is operating and so that, when the system of phonographs is out of operation but main line switch 14 closed, there will be lit that one of the pilots whose phonograph will first operate upon resumption of system operation. In Figure 1 I have shown the attendant's pilots for the respective phonographs as 259 and 259', each again preferably of the abovementioned neon type, and each arranged to light in the recited manner. Extra contacts 22c and 22c' are provided in the respective phonographs in alignment with the contacts 22—22a and 22'—22a' therein and adapted to be touched by the respective arms at the same times as those contacts (i. e., when the respective arm is in run position); and each attendant's pilot, in series with a respective high resistance 251 or 251', is connected from a respective one of the contacts 22c and 22c' to conductor 11 through a respective conductor 252 or 252' and common conductor 253, and so is lit whenever the respective phonograph either operates or (the system being out of operation) will be the next to operate. I have shown these connections to conductor 11, however, made through a common high resistance 254, and this resistance shunted by a switch 322c electrically connected to conductor 253 and mechanically incorporated in the magnet assembly 400 as were the contacts 22c and 22c' in the other magnet assemblies. The function of this special arrangement is to cause each pilot to reduce its brilliance when it is indicating merely the adaptation of its phonograph for next operation (i. e., when control arm 327 is in stop position)—this giving the attendant a visual dis-

inction from the case of actual phonograph operation.

It will be understood that the high resistances mentioned in connection with the above described indicating means—in particular the dictator's two pilots—are of values sufficient to limit the currents therethrough to materially less than required for actuation of the several start and stop magnets; typically they may have resistance values in the tens-of-thousands of ohms. In the case of phonograph pilot 290 it is desirable that resistance 291 be at least as small and preferably smaller in value than each of the resistances 293 and 293', so that good contrast of brilliance may be obtained according to whether one, or both in parallel, of the resistances 293 and 293' is effectively in series with the pilot. In the case of the attendant's pilots 250 and 250', it is desirable that the resistance 254 be of appreciable value relative to each of the resistances 251 and 251', in order that the lamp brilliance will be significantly varied according to the position of control arm 327.

One further indicating means for the attendant is very desirably, and with the protective circuit according to my invention very simply, provided. This consists in a warning device for apprising the attendant of the stoppage of the system because of lack of sound box restoration; it is provided by serially inserting in the protective circuit, for example in conductor 57a in the coupling unit, a filamentary lamp 249 or other indicating device (audible if desired) normally operable on low voltage and on at least as little current as is passed through the protective circuit during its continued closure. (When the current required for normal operation of the device 249 is less than such protective circuit current, there is permitted the shunting of the device as by a resistance 248; this has of course the advantage of maintaining the protective circuit operative in spite of a possible open-circuiting defect in the device 249.) Of course the device (as shunted if resistance 248 be employed) must be capable of withstanding momentarily the higher current which passes through the protective circuit at the instant of closing thereof and before the control arm 327 has thrown to stop position and reduced the protective circuit current.

Many of the important features of my invention may be incorporated in an alternative photographic system, such as I have illustrated in Figure 2. The most essential difference of the system of Figure 2 from that of Figure 1 lies in the omission of the coupling unit D; and in the use of an entirely revised control station S, which in general performs the functions performed in the system of Figure 1 by the control station C and coupling unit D together.

In Figure 2 the phonograph B and its internal wiring may be identical with phonograph B of Figure 1 (excepting for example that the protective circuit indicating device 249 and its shunt resistance 248 may be inserted in the conductor 57a within the phonograph B in view of the omission of the coupling unit, wherein it was before conveniently located). Phonograph A and its internal wiring may likewise be identical with phonograph A of Figure 2, excepting that certain connections of conductors (principally conductors leading to the control station) formerly made in the coupling unit are now made in the lower-right-shown corner of phonograph A.

In Figure 2 purely exemplary polarities have

again been noted for convenience, it being again understood that the system is again impervious to polarity, and may be used as well on alternating current. It is now convenient to introduce the positive line conductor 12, rather than a conductor 12a, directly into the two phonographs, and this time to extend the negative line conductor to the main line switch 414 in the control station. After passing through this switch (which will be assumed closed for purposes of further description) this conductor has been designated as 11a, and leads to the contact spring 427 of a multi-contact switch assembly 500; this spring may be considered as forming the common control arm for the system, analogous to the control arm 327 of Figure 1. It is illustrated in stop position, to which it is biased—i. e., out of contact with a lower-illustrated contact spring 422b—but it is adapted for downward movement to close thereagainst, and thus to come into run position, by means hereinafter described. The contact spring 422b is generally analogous to the contact 322b of Figure 1, and to it may be led (for example out of phonograph A) the conductor 11b.

The immediate means by which the dictator may at will position the control 427 in stop and run positions are a pair of start and stop buttons 481b and 480b, for example projecting upwardly through free holes in a station top-member 501. Each button may have a respective downward extension 481c or 480c freely passing through an appropriate hole in a sub-top 502; may be provided with a respective shoulder 481d or 480d below the top-member 501; and may be biased upwardly by a respective expansion spring 481e or 480e encircling its downward extension between its shoulder and the sub-top. The start button 481b has a further extension or push-rod 503 extending downwardly at least substantially into contact with the top of contact spring 422—a switch 500 component hereinafter more particularly referred to, but here noted as positioned above control arm 427 and biased to be slightly out of contact therewith when the latter is in stop position. Thus slight depression of start button 481b serves to close spring 422 against control arm 427, while appreciable depression thereof serves to move control arm 427 into run position (of contact with spring 422b); if this appreciable start button depression be maintained against the bias of the switch springs, the arm 427 will be maintained in run position.

Means are provided for automatically maintaining this appreciable start button depression. These consist in a latch 504 forming a portion of a slidable latch-plate 505 located under the sub-top, and a latch-engaging member 506 carried by the start button extension 481c below the sub-top. The sliding limits of the latch-plate 505 may be established by the longitudinal length of slots 507, through which may freely pass stationary retaining screws 508; it is biased leftwardly, as illustrated, by the spring 509, and is shown in its extreme leftward position. As start button 481b is depressed the member 506 causes the latch and latch-plate to move slightly rightwardly; but as the member 506 approaches the sub-latch plate edge 510, the plate springs leftwardly again, and the latch holds the member 506 engaged, the start button depressed, and the control arm 427 thus in run position. The stop button 480b is arranged so that its momentary depression releases the latch and permits the arm 427 to come again into stop position in response

- to its bias, raising the start button. Thus generally underneath the stop button the latch-plate may be provided with a cam-edge 511; and a cam-engaging member 512 is carried by the stop button extension 480c so as normally to be in substantial contact with this cam-edge. As the start button is depressed the sliding of member 512 along the cam edge forces the latch plate sufficiently rightwardly so that the latch disengages the member 506 to release the start button, control arm 427, etc. It will be understood, of course, that the shown and described arrangement of latch-plate, and association thereof with the start and stop buttons, is intended only to illustrate a typical means for automatically maintaining the start button depressed, and for releasing it in response to stop button depression, and that the arrangement is in no way intended as limitative.
- 10 It will now be seen that, in response to depression of start button 481b by the dictator, the control arm 427 will come into and remain in run position, connecting conductor 11b with the negative supply line 11 and causing the operation of any phonograph then having its individual control arm in run position; this is of course a similar effect to that of depression of the start button 381b of Figure 1 (the only operative distinction being that in Figure 2 the start button remains depressed after the required momentary manipulation). It will also be seen that, in response to momentary depression of stop button 480b by the dictator, the control arm 427 will come into and remain in stop position, disconnecting conductor 11b from the supply line and stopping operation of any phonograph then operating; this again is a similar effect to that of depression of the stop button 380b of Figure 1. The automatic system of starting and stopping circuits functions in the same manner as in Figure 1. And since the protective circuit and its functions are retained, as described immediately hereafter, it will be seen that the use of the system is quite similar to that of the system of Figure 1. As with that system, whenever the control arm 427 is in run position there is in operation one (or during overlaps, two) of the phonographs; and there always remains in run position at least one of the individual control arms 27, 27'.
- 15 Attention may now be directed to the protective circuit in Figure 2, which within the two phonographs is of course similar to that of Figure 1 and is closed under identical conditions with those therein. The conductor 51b which in that figure led into the coupling unit is now led to the control station, and in the latter is provided the device, responsive to circuit closing, for throwing the common control arm 427 to stop position. This device may now simply comprise means for causing the latch to release the member 506; it has been illustrated in Figure 2 as a solenoid 420 arranged upon actuation to pull rightwardly a plunger 420a, of magnetic material such as iron, secured to the latch-plate, and hence the latch-plate itself. As in Figure 1, the protective circuit is desirably completed to the negative line conductor (in this instance to 11a) through a resistance which is shorted out by a switch when the common control arm 427 is in run position. This resistance appears in the control station S as 496, and this switch as that formed by the spring 422, already described, and the control arm 427.
- 20 As in the case of Figure 1 it is desirable that

there be provided some means operative while the protective circuit is closed for preventing even a temporary starting of the motors by depression of the start button; in Figure 2 such means, in mechanical form, are provided and operate (as in Figure 1) to prevent throwing of the control arm 427 to run position. This means comprises a stop-edge 513 provided on latch-plate 505 to the left of and at a higher level than the sub-latch plate edge 510 and preferably joined therewith by a cam edge 514. The range of movement of the latch-plate is made (as by the slots 507) sufficient so that the solenoid 420 will move it to bring the stop-edge 513 under at least a portion of member 506; thus when the solenoid is energized the stop-edge 513 forms a down-stop for the start button 481b and prevents full depression thereof. Of course as the solenoid acts, the opening of contact 422 from contact 427 throws in series therewith the resistance 496; and unless this resistance be of sufficiently low value the solenoid energization will be rendered too weak to overcome spring 509 and the latch will return leftwardly. But this effect is permissible; for in the very first portion of any attempted re-depression of the start button spring 422 will be closed against arm 427 and (if the protective circuit still be closed) the solenoid will be fully energized, instantly pulling the latch rightwardly to get the stop-edge 513 under the lowering start button. (Thus resistance 496 is not necessarily provided in the protective circuit for the purposes of the resistance inclusion therein in Figure 1; it is primarily included for reasons, hereinafter apparent, having to do with the indicating system.) It will now be seen that the protective circuit not only responds as did the protective circuit of Figure 1, but produces the same ultimate effects as did that circuit—though by somewhat different means, appropriate to the altered dictator's control system.

The prevention of temporary phonograph starting by start button depression while the protective circuit remains closed may if desired be accomplished alternatively by electrical rather than mechanical means; this has been illustrated in Figure 2a—a fractional control station view intended for optional substitution for the corresponding portion of Figure 2. Herein the possible rightward latch-plate movement may be limited to just enough for dependable latch release, as by the employment of restricted-length slots 507'; and the stop-edge 513 (and cam-edge 514 joining it with sub-latch edge 510) need not be provided. While the protective circuit device for releasing the latch may be the solenoid 420 of Figure 2, it is permissible in view of the restricted latch-plate movement to employ instead thereof an electromagnet; this has been illustrated as 520, having fixed core 520c, and arranged upon energization to attract an armature 520a secured to the latch-plate and hence the latch-plate itself. The electrical means for preventing improper motor starting consists simply in a switch 519, having the pole 519a biased to close the switch, and serially inserted in the conductor 11b; the pole 519a is arranged to be moved by rightward movement of the latch-plate so that switch 519 is opened preferably just before member 506 is passed by the latch. When and as long as start button 481b is even slightly depressed during protective circuit closure, the full electromagnet energization (resulting from closing of contact 422 against control arm 427) will keep the latch-

plate rightwardly attracted, switch 519 open, and the phonographs thus incapable of starting.

There remain finally to be considered in Figure 2 (or 2a) the attendant's and dictator's indicating means; these have been somewhat differently incorporated both for the purpose, in the case of the dictator's means, of a simplification appropriate to the revised control station, and generally for the purpose of minimizing the number of conductors required to and from the control station.

The attendant's warning device 249 has already been mentioned. The attendant's pilots 250 and 250', each in series with the respective high resistance 251 or 251', are inserted as before in the respective conductors 252 and 252' and each of these conductors connected at one end to the respective magnet assembly contact 22c or 22c'. At their other extremities, however, these conductors are not connected to the negative supply line in the manner shown in Figure 1, but are connected with that protective circuit conductor—57b—which extends to the control station. So long as the protective circuit is open this conductor is rendered at negative line potential, either through the solenoid 420 only if the control arm 427 is in run position and thus at least one phonograph operating, or through the solenoid and resistance 496 if the control arm is in stop position and thus neither phonograph operating. Thus these pilots will be lit at the same times as in the case of Figure 1—subject only to the exception that they will be extinguished when the protective circuit is closed (by virtue of a then positive potential of conductor 57b), at which time the attendant however has the then most essential indication provided by the warning device 249. And the resistance 496, of course in increasing degree as it is made larger, provides, as in Figure 1, some contrast of brilliance between operation and adaptation-for-next-operation indications.

In the system of Figure 2 up and down positions of the start button 481b themselves form indications of phonograph operation and non-operation; in combination, then, with such an indication I have combined for the dictator the indications of a single pilot 560. When the start button is depressed, illumination of this pilot at a moderate brilliance indicates that one phonograph is operating and illumination at high brilliance that two are operating; when the start button is up any illumination of this pilot indicates readiness of the system for operation upon depression of that button. To achieve this result I connect one terminal, of the combination of pilot 560 and its series high resistance 561, to a conductor 559 leading therefrom for example into phonograph A, and to this conductor I connect the conductors 292 and 292' of Figure 1 (each of which leads through a respective high resistance 293 or 293' to a respective magnet assembly contact 22a or 22a'). The other terminal of the pilot-resistance combination 560—561 I connect to negative conductor 11a when the control arm 427 is in run position, and to the conductor 57b when that arm is in stop position. In the run position case the combination is therefore connected across the supply line—through one of the resistances 293 and 293' if one phonograph operates (one arm 27 or 27' in run position), and through both of these resistances if both phonographs operate (both arms 27 and 27' in run position), thus providing the contrast of brilliance. In the stop position case the combination

is connected, through one or both of the resistances 293 and 293' and through solenoid 420 and resistance 496, across the line so long as the protective circuit is open and the system thus in readiness for operation upon start button depression; if, however, the protective circuit is closed and the system thus inoperable, conductor 51b is at positive potential and no voltage appears across the pilot to illuminate it. The selective connection of the second-mentioned terminal of the pilot-resistance combination 560—561 may be effected by a contact spring 562 included in the switch assembly 500 below arm 427, and to which that terminal is wired; when arm 427 is in stop position this spring is touched from underneath by a contact spring 563, which is wired to conductor 57b. The spring 563, however, is linked to the arm 427 by an insulating tie-rod or -block b''; and when arm 427 is moved downwardly to run position it both moves spring 563 out of, and itself comes into, contact with spring 562.

While throughout the specification I have described the phonographic systems and their operations, and the various features of my invention, in terms of specific embodiments thereof, I intend thereby no unnecessary limitations; rather I intend in the appended claims to claim my invention, and all its novel sub-combinations, elements and individual features, as broadly as the state of the art will permit.

I claim:

1. In combination, a plurality of phonographs, each having a sound box element adapted for progressive movement relative to a record element; an automatic control system for maintaining said phonographs in sequential operation; other control means connected in common with all phonographs; and means, responsive to said elements when they become adjacent their respective movement limits in all phonographs, for actuating said common means to place all phonographs out of operation.

2. In combination, a plurality of phonographs, each having a sound box element adapted for progressive movement relative to a record element; an automatic control system for maintaining said phonographs in sequential operation; other control means connected in common with all phonographs and actuatable selectively to initiate said phonograph operation and place all phonographs out of operation; and means, responsive to said elements when they become adjacent their respective movement limits in all phonographs, for blocking actuation of said control means which initiates phonograph operation.

3. In combination, a plurality of phonographs arranged for sequential operation, each having a sound box element adapted for progressive movement relative to a record element; control means connected in common with all phonographs and actuatable selectively to initiate said phonograph operation and place all phonographs out of operation; and means, responsive to adjacency of said elements in all phonographs to their respective movement limits, for actuating said control means to place all phonographs out of operation and for blocking actuation of said control means to initiate phonograph operation.

4. In combination, a plurality of phonographs each having a sound box element adapted for progressive movement relative to a record element; an automatic control system energizable to maintain said phonographs in sequential phono-

- graph operation; a single switch throwable to energize and to de-energize the entire said system; and means, responsive to said elements when they become adjacent their respective movement limits in all phonographs, for throwing said switch to de-energize said system.
5. In combination, a plurality of phonographs each having a sound box element adapted for progressive movement relative to a record element; individual control means for each phonograph; an automatic system arranged for energization to actuate the several individual means for sequential phonograph operation; a control means connected in common with all phonographs; and means, responsive to adjacency of said elements in all phonographs to their respective movement limits, for actuating said common means to place all phonographs out of operation.
6. In combination, a plurality of phonographs each having a sound box element adapted for progressive movement relative to a record element; an automatic control system energizable to maintain said phonographs in sequential operation; other control means connected in common with all phonographs; and means, responsive to said elements when they become adjacent their respective movement limits in all phonographs, for de-energizing said automatic system and actuating said common means to place all phonographs out of operation.
7. In combination, a system of phonographs each operable for limited record traversal; means for operating said phonographs in predetermined mutual relationship; a control device connected in common with all said phonographs; and a protective circuit and means for closing the same in response to a condition of substantial completion of said traversals in all phonographs, said protective circuit serially including a source of current and current-responsive means for actuating said control device to place said system out of operation.
8. In combination, a system of phonographs each operable for limited record traversal; means for operating said phonographs in predetermined mutual relationship; a control device connected in common with all said phonographs; and a protective circuit and means for closing the same in response to a condition of substantial completion of said traversals in all phonographs, said protective circuit serially including a source of current, an indicating device, and current-responsive means for actuating said control device to place said system out of operation.
9. In combination, a system of phonographs each having a sound box element arranged for progressive movement relative to a record element; a protective circuit interlinking the several phonographs; means, responsive to adjacency of said elements in all phonographs to their respective movement limits, for closing said circuit; and means, responsive to closing of said circuit, for placing said system out of operation.
10. In combination, a system of phonographs each having a sound box element arranged for progressive movement relative to a record element; a normally open switch in each phonograph arranged to be closed as said elements approach their movement limit; and a protective circuit serially including all said switches and means responsive to their joint closing for placing said system out of operation.
11. In combination, a plurality of phonographs each having a sound box element adapted for progressive movement relative to a record element; an individual movement control system associated with each phonograph comprising momentarily actuatable means for starting and momentarily actuatable means for stopping said movement; means in each one phonograph operative as a limit of said movement therein is approached for actuating said starting means of another phonograph and said stopping means of the one phonograph; switch means in each phonograph arranged for closing before operation of said actuating means therein; and a protective circuit serially including said switch means of all phonographs and means responsive to the joint closing of all said switch means for placing said system out of operation.
12. In combination, a plurality of phonographs each operable for limited record traversal; means for operating said phonographs in predetermined mutual relationship; a selectively throwable control member having run and stop positions, connected in common with all said phonographs; a protective circuit and means for closing the same in response to a condition of substantial completion of said traversals in all phonographs; electromagnetic means for throwing said control member to stop position, and means for passing an actuating current therethrough upon closing of said circuit; and means operative after initial closing and during continued closing of said circuit for passing through said electromagnetic means a reduced current of sufficient strength to maintain said control member in stop position.
13. In combination, a plurality of phonographs; an individual control member for each phonograph having run and stop positions; a system for automatically moving said members for sequential phonograph operation while at any time leaving at least one of said members in run position; control means connected in common with all phonographs for causing and stopping phonograph operation; and common indicating means for all phonographs, responsive to said individual control members differentially in accordance with the number thereof in run position.
14. In combination, a plurality of phonographs; means for maintaining said phonographs at will in sequential, overlapped operation; an indicating device and means for passing current therethrough; and means responsive to the number of phonographs operating for regulating said current.
15. In combination, a plurality of phonographs each operable for limited record traversal; means for operating the same in predetermined mutual relationship; means comprising a protective circuit for placing all said phonographs out of operation in response to a condition of substantial completion of said traversals in all phonographs; an indicating lamp having a minimum ignition voltage, and means normally operative to impress a higher voltage thereacross; and means responsive to protective circuit operation for reducing the voltage across said lamp to a finite voltage less than said minimum ignition voltage.
16. In combination, a plurality of phonographs each operable for limited record traversal; an individual operation control member for each phonograph; means for moving said members to operate said phonographs in predetermined mutual relationship; a switch connected in common with all phonographs and movable at will to

run and stop positions; protective circuit means for throwing said switch to stop position in response to a condition of substantial completion of said traversals in all phonographs; an indicating lamp and means for illuminating the same; and selective means associated with said switch, operative when said switch is in run position to render said lamp responsive to said individual control members, and when said switch is in stop position to render said lamp responsive to said protective circuit.

17. The combination according to claim 9, further including an indicating device responsive to the condition of said circuit.

18. In combination, a plurality of phonographs; means for maintaining said phonographs in sequential operation; means movable to cause the suspension and resumption of said operation; indicating devices for the several phonographs respectively and means for passing current through each said device when its said respective phonograph is operating; and means, rendered operative by an operation-suspending movement of said movable means, for passing a modified current through that device whose

phonograph will first operate upon resumption of said sequential operation.

19. In combination, a plurality of phonographs each having a sound box element adapted for progressive movement relative to a record element; a common circuit for supplying power to said phonographs; an automatic control system for maintaining said phonographs in sequential operation; and other control means, responsive to said elements when they become adjacent their respective movement limits in all phonographs, for breaking said common circuit.

20. In combination, a plurality of phonographs each having a sound box element adapted for progressive movement relative to a record element; a common circuit for supplying power to said phonographs; an automatic control system energizable to maintain said phonographs in sequential operation; and other control means, responsive to said elements when they become adjacent their respective movement limits in all phonographs, for breaking said common circuit and de-energizing said automatic system.

CHARLES T. JACOBS. 25

CERTIFICATE OF CORRECTION.

Patent No. 2,146,434.

February 7, 1939.

CHARLES T. JACOBS.

It is hereby certified that error appears in the printed specification of the above numbered patent requiring correction as follows: Page 4, first column, line 39, for "contact 2'" read contact 22'; page 5, second column, line 45, after "dictator" insert may; page 7, second column, line 27, after "control" insert arm; page 9, second column, line 54, claim 2, after "blocking" insert that; and that the said Letters Patent should be read with this correction therein that the same may conform to the record of the case in the Patent Office.

Signed and sealed this 11th day of April, A. D. 1939.

(Seal)

Henry Van Arsdale
Acting Commissioner of Patents.
